UNITED STATES PATENT OFFICE.

CONSTANT VIAN, EDOARDO BECCHIO, AND VITTORIO BECCHIO, OF BROOKLYN,
NEW YORK.

DESIGN FOR A LINK FOR MATS.

SPECIFICATION forming part of Design No. 23,627, dated September 4, 1891.

Application filed May 18, 1894. Serial No. 511,724. Term of patent 7 years.

To all whom it may concern:

Be it known we, CONSTANT VIAN, EDOARDO BECCHIO, and VITTORIO BECCHIO, all citizens of the United States, and residents of Brooklyn, Kings county, New York, have invented and produced a certain new and useful Design for a Link for Mats, of which the following is a specification.

The design described herein relates to a link for mats, such as door mats, elevator mats, car mats, &c.

The accompanying drawing, forming a part of this specification, shows a perspective view of the link embodying our design.

The leading features of our design consist in the link *a*, said link having a series of scallops *b* in its upper and lower edges or faces, as shown. In the upper face there are four

scallops of equal size and on the lower face there are three scallops; that is, one small central scallop and two larger flanking scallops.

We claim as our invention—

The design for a link for mats having an elongated contour with a series of scallops of uniform size in one face and a series of scallops in its other face consisting of a small central scallop and two larger flanking scallops, substantially as shown and described.

CONSTANT VIAN.
EDOARDO BECCHIO.
VITTORIO BECCHIO.
